UNITED STATES PATENT OFFICE.

HARLOW DOW SAVAGE, OF ASHLAND, KENTUCKY.

BAFFLE-WALL FOR LOCOMOTIVE FIRE-BOXES.

1,033,952.

Specification of Letters Patent. Patented July 30, 1912.

Application filed June 1, 1911. Serial No. 630,581.

To all whom it may concern:

Be it known that I, HARLOW D. SAVAGE, a resident of Ashland, in the county of Boyd and State of Kentucky, have invented a new and useful Improvement in Baffle-Walls for Locomotive Fire-Boxes, of which the following is a specification.

This invention relates to baffle walls for locomotive fire boxes.

10 The object of the invention is to improve the arrangement of fire brick forming such baffle walls in order to facilitate repair of tubes, reduce the cost of fire brick, and for convenience of handling.

15 In the accompanying drawing Figure 1 is a longitudinal section through a fire box provided with my improved baffle wall; Fig. 2 is a transverse section on the line 2—2, Fig. 1; Fig. 3 is a plan view of the 20 baffle; and Figs. 4, 5 and 6 are perspective views of the brick.

In the drawings 1 represents the front wall of the locomotive fire box provided with a firing opening 2; 3 represents the 25 rear wall of said fire box; 4 the top thereof, and 5 the grate. Extending between the front and rear side walls are the usual longitudinal tubes 6 for supporting the baffle wall. The fire box is provided with four 30 longitudinal tubes 6, which, as shown, are connected in the circulation of the boiler and extend substantially parallel to the central longitudinal vertical plane of the fire box, at least for those portions of their 35 length which support the baffle wall, and, as shown in Fig. 1, are inclined longitudinally of the fire box.

The baffle wall 7 is formed by a series of brick supported upon the longitudinal tubes 40 6, there being one row of brick between each two adjacent tubes and between each side tube and the side walls of the fire box. As shown, there are five rows of brick, to wit, the central row 8, two intermediate rows 9, 45 and two extreme side rows 10. The central and intermediate rows are formed of brick of the same shape, except for length, each brick having its ends beveled both from the top and bottom, as at 11 and 12, to provide 50 an acute wedge-like end. The beveled faces 12 rest upon the tubes 6, so that a portion of the body of each brick extends downwardly between the tubes, thereby assisting in holding the brick against lateral displacement. These latter beveled faces however 55 permit the ends of the brick to slide up

somewhat on the tube to compensate for expansion and contraction. It will be observed that the meeting ends of two contiguous brick have their apexes opposite each other, so that in case one brick should move materially laterally it can move up over the inclined face 11 of the brick in the next adjacent row. This double beveling of the ends of the brick therefore permits the brick to move more or less laterally under extreme conditions of expansion and contraction, permitting the ends of adjacent brick to pass each other if necessary.

The brick of the side rows 10 are beveled only at their inner ends, the outer ends preferably being somewhat square and preferably supported on hollow projections or bushings 15 secured to the side walls of the fire box.

75 The longitudinal edges of the brick are rabbeted, as shown at 16, so as to provide overlapping portions whereby each brick is supported to some extent upon the adjacent brick and forming rows of brick in which each brick has such support upon the adjacent brick that it is not readily tipped or tilted out of place. The rearmost brick of each of the rows is preferably provided with an extension or projection 17 bearing 80 against the rear side wall of the fire box, and leaving spaces 18 at such wall through which flame can pass.

85 The brick described are of simple shape, cheap to manufacture, and can be very 90 readily put in place and removed. The ends thereof are such that brick of adjacent rows cannot fuse together and the construction is such that while the brick are free to move laterally somewhat and pass each other, they nevertheless have portions depending between the tubes to prevent lateral displacement due to the jolting or jarring of the locomotive. The several brick of each row mutually support each other on 95 account of the overlapping portions thereof, and these portions also form a broken joint to prevent flame and hot gases from passing through.

100 What I claim is:

1. A locomotive fire box comprising in combination, side walls, longitudinally inclined circulation tubes extending between the side walls and laterally disposed in a horizontal plane, and rows of brick on said 105 tubes, the ends of said brick being beveled from both sides to provide end portions hav-

- 2.
- ing upper and lower inclined faces at each end thereof, the lower inclined faces at opposite ends resting at a line on and fitting adjacent tubes, adjacent rows of said brick 5 presenting wedge-like ends toward each other, whereby the lower inclined faces of said brick can move laterally and ride upon the upper inclined faces of adjacent brick with contraction and expansion.
- 10 2. A locomotive fire box comprising in combination, side walls, longitudinally inclined circulation tubes between the side walls and laterally disposed in a horizontal plane, and rows of brick on said tubes, the 15 ends of said brick being beveled from their upper and lower faces and of acute wedge-shape, the lowermost brick of each row having a flat side face and being provided with

a projection extending beyond the flat side face of said brick and bearing against the 20 rear side wall, all of said brick being adapted to be placed on said tubes with either the upper or lower beveled faces resting upon and fitting the same and with a portion projecting down therebetween, whereby the inclined faces resting upon said tubes can move laterally and ride upon the upper inclined faces of adjacent brick with contraction 25 and expansion.

In testimony whereof, I have hereunto set 30 my hand.

HARLOW DOW SAVAGE.
